UNITED STATES PATENT OFFICE.

GEORGE HENRY THOMPSON, OF READING, AND WILLIAM H. ROTHERMEL,
OF MAIDEN CREEK, PENNSYLVANIA.

• WASHING-MACHINE.

SPECIFICATION forming part of Letters Patent No. 340,168, dated April 20, 1886

Application filed November 10, 1885. Serial No. 182,324. (No model.)

To all whom it may concern:

Be it known that we, GEORGE H. THOMPSON and WILLIAM H. ROTHERMEL, of Reading and Maiden Creek, respectively, in the county of Berks and State of Pennsylvania, have invented certain new and useful Improvements in Washing-Machines; and we do hereby declare the following to be a full, clear, and exact description of the invention, such as will enable others skilled in the art to which it appertains to make and use the same.

Our invention relates to that class of washing-machines in which the clothing and other articles washed are subjected to the rolling pressure of rollers in the suds instead of being rubbed, and its object is to provide a machine of this class with an improved reticulated supporting-bed for the articles to be washed, and to provide such machines with automatic soap-distributors, whereby soap will be continuously applied to the articles being washed.

With these objects in view the invention consists in certain novel constructions and combinations of devices, which will be readily understood from the following particular description, and the novel features of which will be definitely pointed out in the appended claims.

30 In the drawings, Figure 1 is a perspective view of our improved washing-machine closed. Fig. 2 is a similar view of the same with the lid raised. Fig. 3 is a detached view of one of the staples for supporting the rollers and soap-boxes. Fig. 4 is a longitudinal section through the roller-supporting bar and rollers, and also through the lid and bevel gear-wheel above the same. Fig. 5 is a detached view of one of the soap-boxes. Fig. 6 is a side elevation of the rotary bar with a modified arrangement of corrugated rollers.

The letter A indicates the body or box of the machine, which is mounted on legs *a a*; and C is the lid hinged to the top edge of one side wall of the box. Within the box sits a round basket, E, of wicker-work. It may be woven of splints, rattan, or willow, or of any other material, so that it will be elastic, but firm enough to well hold its shape. 45 The basket is of such diameter that it fits tightly in the box and presses against the four

sides thereof. This basket forms the bed which supports the articles being washed. A stout bar, F, preferably of wood, is arranged directly under the lid C, being firmly secured to a spindle, G, which extends up through a thimble, h, which is fixed at the center of the lid. Above the lid a horizontal bevel gear-wheel, H, is fixed upon the spindle, and with it meshes a vertical bevel gear, I, mounted on a horizontal trunnion, k, which has its bearing in a sleeve, l, supported on short legs *m*.

To one end of the trunnion *k*, or to the gear I, is fixed a handle, N, by which said gear 65 may be rocked and motion transmitted from it through the bevel-gear H and spindle to the bar F, which may be thus rotated alternately in opposite directions.

On opposite sides of middle point of bar F 70 are secured downwardly-projecting staple-like frames of metal—such as shown at P in Fig. 3—said frames having shoulders *q*, of india-rubber, secured around their corners.

Loosely surrounding the legs of the frames P, above the shoulders *q*, are corrugated rollers R, which may be made of any suitable material—say brass, iron, or wood.

Upon the cross-bars which connect the lower ends of the legs of frames P the soap-boxes S are mounted between shoulders *q q*. Each soap-box is perforated with numerous holes, and is preferably shaped as a longitudinally-corrugated oblate ellipsoid, though it may be simply cylindrical with rounded 85 ends, and each is divided longitudinally into two halves fitting together like a pill-box with the edge of one entering tightly in the other. Each half-box has its wall at its ends cut away to form a semicircular recess or 90 half-bearing, so that the half-boxes may be put together around the cross-bars of the frames P to form complete boxes revoluble on said cross-bars.

The operation of the machine is as follows: 95 The articles to be washed are placed in the basket C, and the box is supplied with a sufficient quantity of water to cover them, the soap-boxes are filled with soap, preferably finely cut, and placed on the cross-bars of the frames, and the lid C being then shut down the handle N is vibrated back and forth.

The bevel-gear I being much greater in diameter than the gear II on the spindle G, the bar F carried by said spindle makes about a complete rotation for each half-vibration of 5 the handle, the rotations of the bar being alternately in opposite directions. During the rotations of the bar the corrugated rollers R press the clothes against the wall of the basket, and squeeze them tightly as they 10 roll, causing the water to surge through the clothes, and also through the interstices of the basket, which on account of this permitting of the water to pass, and owing to its elasticity, we find to be far preferable to rigid 15 imperforate beds, either corrugated or plain. The rubber-shoulders q q drag the clothes back and forth, continually changing their position, so that a different portion of the mass is presented to the rollers at each rotation 20 thereof. As the rollers are revolved the soap-boxes roll over these portions of the clothes which are at the bottom of the basket, applying soap evenly and plentifully to them as the water is forced through the boxes, so that as 25 the articles at the bottom are dragged along and in turn caught by the rollers they will be well soaped and ready for the squeezing action of said rollers.

The box is provided with a plug, t, so that 30 the water may be drawn off when desired.

In Fig. 6 is shown a modified arrangement of the corrugated rollers on the rotating bar F. Between the two rollers R R of each pair a pin, p, projects downward from the bar, 35 and upon said pin is loosely mounted a corrugated roller, R', of a diameter to nearly fill the space between the two rollers R R while being clear of the soap-box below. This large roller operates upon clothes in the same 40 manner as the others, and greatly facilitates the washing, though it is not absolutely necessary.

We do not confine ourselves to the precise details of construction as shown in our drawings, but may vary the same in any manner 45 for the better carrying out of the principle of our invention without departing from the true spirit thereof. For instance, we may substitute for the woven basket a zinc or other metallic corrugated and perforated box or pan 50 of similar shape.

Having fully described our invention, what we claim as new, and desire to secure by Letters Patent, is—

1. In a washing-machine, the combination, 55 with the box, of the reticulated or perforated inclosed basket, the rotary bar and loosely-mounted rollers depending therefrom, and mechanism for supporting and rotating said bar, substantially as described. 60

2. In a washing-machine, the combination, with the box, its lid, and the rotary support pivoted to the under side of said lid, of the staple-like frames depending from said rotary support, and the corrugated rollers and soap- 65 boxes mounted on said frames, substantially as described.

3. In a washing machine, the combination, with a revolving clothes-pressing device, of the loose perforated soap-boxes, substantially 70 as described.

4. In a washing-machine of the kind described, the combination, with the rotary bar, of the depending staple-like frames having the elastic shoulders q q, and the corrugated 75 loose rollers, substantially as described.

In testimony whereof we have signed this specification in the presence of two subscribing witnesses.

GEORGE HENRY THOMPSON.
WILLIAM H. ROTHERMEL.
